United States Patent Office.

WILLIAM WEAVER, OF PHÆNIXVILLE, PENNSYLVANIA.

Letters Patent No. 63,445, dated April 2, 1867.

IMPROVED MACHINE FOR COILING WIRE.

The Schedule referred to in these Letters Patent and making part of the same.

TO ALL WHOM IT MAY CONCERN:

Be it known that I, WILLIAM WEAVER, of Phoenixville, Chester county, Pennsylvania, have invented a Machine for Coiling Wire to form Springs, &c.; and I do hereby declare the following to be a full, clear, and exact description of the same, reference being had to the accompanying drawing, and to the letters of reference marked thereon.

My invention consists of mechanism, fully described hereafter, whereby wire may be quickly and easily coiled, to form springs and other articles.

In order to enable others skilled in the art to make and use my invention, I will now proceed to describe its construction and operation, reference being had to the accompanying drawing, which forms a part of this specification, and in which—

Figure 1 is a sectional elevation of my improved machine for coiling wire.

Figure 2, a side elevation.

Figure 3, a plan view.

Figure 4, a detached sectional view of part of the machine; and

Figure 5, a section on the line 1-2, fig. 4.

A is a wooden frame, which consists of side-pieces *a a'* and cross-pieces *b b'*, the whole being supported on suitable legs *c c*. To the cross-piece *b* are secured a stationary standard, B, and an adjustable standard B', a portion, *d*, of the latter projecting through a slot, *x*, in the cross-piece *b*, to which it is confined by a detachable key, *e*. In the standard B turns a spindle, *c*, to the outer end of which is secured a crank-handle, *f*, and into a groove, *y*, in the spindle projects the upper end of a sliding plate, *g*, which is so secured to the standard B as to be readily adjusted vertically thereon. To the inner end of the spindle C is secured one section of a metal "former," D, which former, in the present instance, consists of two conical sections, *h h'*, and an intermediate cylindrical section, *i*, a rod or shaft, C', secured to the section *h'*, projecting through the standard B', and having on the outside of the standard a thumb-nut, *k*. A screw projection on the section *h* is adapted to a corresponding recess in the intermediate section *i*, and at the opposite end of the latter is a square projection fitting into a corresponding orifice in the section *h'*. In the surface of the former D is cut the spiral groove shown in fig. 3, and in the section *h* are a number of openings, *j*, to any of which may be fitted a detachable pin or staple, *m*. At the rear of the frame A turns a detachable shaft, E, and to this shaft is secured a reel, F, containing a coil of wire, *t*, from which springs and other articles of coiled wire are to be formed. The wire *t* passes between the jaws *n n'* of a tension-guide, G, the two jaws being hinged together at *r*, and the distance to which they can be separated being regulated by a set-screw, *s*. At the inner end of the jaw *n'* is a projection, *q*, in which is a recess, *u*; and in the upper surface of the jaw, near one side of the same, is a recess, *o*, fig. 5.

The operator seats himself on the cross-piece *b'*, passes the wire *t* through the tension-guide G, and into the groove *o*, as shown in figs. 2 and 4, and secures the end of the wire to the pin *m*. He then takes the tension-guide G in his left hand, and with his right turns the spindle C, by means of the handle *f*, so as to impart a rotary motion, in the direction of its arrow, to the former D. As the former revolves, the operator holds the tension-guide so that the projection *q* shall bear against the former. He is thus able to hold it in its position, however great the tension may be, while the wire is drawn between the jaws *n n'* through the groove *o* and into the spiral groove *w* in the former. After the wire has been passed once round the former, the tension-guide is so adjusted that the portion of the wire which is above the surface of the former, in the coil already made, shall project into the groove or recess *u* so that, as the former revolves, the spiral wire already on the same shall act as a guiding screw to move the holder towards the section *h'*. The operator will not therefore be required to guide the holder, which will always be in the position required to introduce the wire properly into the spiral groove. If a spring of the entire length of the former is required, the operation is continued until the groove *w* is entirely filled. The wire is then cut, the slide *g* depressed, and the spindle C is drawn back until the three sections *h h'* and *i* can be separated, when the double helical spring coiled on the former may be removed. When a shorter spring is required, the pin *m* is placed in one of the openings nearer the centre of the former, and the wire is then secured to the pin and coiled as before.

Formers of different sizes and shapes may be used to form springs or other articles of coiled wire, differing

in shape from that shown. Intermediate pieces *i* of greater or less length than that shown may be used, or may be entirely dispensed with, the standard *B'* being adjusted as may be required to permit the introduction of the different formers.

The instrument is portable, simple and cheap in construction, and may be used with facility by workmen of ordinary skill.

I claim as my invention, and desire to secure by Letters Patent—

1. The frame *A*, with its standards *B* and *B'*, and revolving former *D*, the whole being constructed, arranged, and operating substantially as and for the purpose described.
2. The tension-guide *G*, consisting of the jaws *n n'*, with the projection *q* and recesses *o* and *u*, the whole being arranged for use in connection with the revolving former *D*, substantially as described.
3. The grooved cylinder *i*, constructed and adapted for attachment to the conical grooved sections *h h'* of the former *D*, substantially as and for the purpose specified.
4. The former *D*, with its openings *j*, adapted for the reception of a detachable pin, *m*, for the purpose set forth.

In testimony whereof I have signed my name to this specification in the presence of two subscribing witnesses.

WILLIAM WEAVER.
